(57) **CLAIM**

The ornamental design for a packaging, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front elevation view of a packaging, showing my new design;

FIG. 2 is a left-side elevation view thereof;

FIG. 3 is a right-side elevation view thereof;

FIG. 4 is a rear elevation view thereof;

FIG. 5 is top plan view thereof; and,

FIG. 6 is a bottom view thereof.

The dash-dash broken lines contained within the drawings form no part of the claimed design.

1 Claim, 6 Drawing Sheets
